United States Patent Office.

PETER SPOHN VAN WAGNER, OF SALTFLEET TOWNSHIP, CANADA.

Letters Patent No. 96,851, dated November 16, 1869.

IMPROVEMENT IN HOLDBACK FOR CARRIAGE-THILLS.

The Schedule referred to in these Letters Patent and making part of the same.

To all whom it may concern:

Be it known that I, PETER SPOHN VAN WAGNER, of the township of Saltfleet, in the county of Wentworth, in Canada, have invented a new and useful Improvement in what is called the "Holdback" for Carriage-Thills, Shafts, or Poles; and I do hereby declare that the following is a full and exact description thereof, reference being had to the accompanying drawings, and to the letters of reference marked thereon.

Figure 1, A, and Figure 2, A, represent a portion of a thill or shaft, on which is fastened the holdback, by means of screws or other suitable fastening.

B represents a chamber, made of malleable cast-iron, or other suitable metal, which is secured to the thill or shaft by screws H H.

C is a spring, secured by means of a screw or rivet, at one end, and presses on a tumbler, D, which works on a pin, I, backward and forward.

G represents a hook, which projects forward from the top of the chamber B.

E is a metal ring, attached to the breeching-strap F.

The tumbler D rotates on the pin I, and allows the ring E to have free play both ways, without becoming disarranged.

The spring C always keeps the tumbler closed or open, as the case may be.

The ring E, attached to breeching-strap F, enters at the hook G, and a slight backward movement fastens it securely, and, when necessary, a forward movement easily releases it.

J is a small semicircular opening, to allow any water that may lodge in the inside to escape.

One side of the tumbler D is rounded a little, so as to admit the ring more easily than when it is being released.

The spring C may be used either in the manner shown on fig. 1 or fig. 2, that is, disclosed to view or concealed, as may be deemed best.

What I claim as my invention, and desire to secure by Letters Patent, is—

The holdback B B, made of malleable cast-iron, or other suitable metal, containing a spring, C, tumbler D, hook G, as above described, applicable to any purpose for which it may be used.

P. S. VAN WAGNER.
